UNITED STATES PATENT OFFICE.

JÓZSEF VIG, OF WITHERBEE, NEW YORK.

PARACHUTE.

1,131,300.

Specification of Letters Patent.

Patented Mar. 9, 1915.

Application filed December 15, 1914. Serial No. 377,353.

To all whom it may concern:

Be it known that I, JÓZSEF VÍG, a subject of the King of Hungary, and a resident of Witherbee, in the county of Essex and State of New York, have invented certain new and useful Improvements in Parachutes, of which the following is a specification.

The present invention relates to improvements in parachute safety devices, specially 10 adapted to be carried by air vessels, such as aeroplanes, balloons, etc.

The main objects of the invention are to provide a parachute that is adapted to be folded into a very small compass when not in use, and which can be conveniently and rapidly extended in case of danger or accident, and which co-operates with an inflatable life saver.

With these and other objects in view,
which will more fully appear as the nature
of the invention is better understood, the
same consists in the combination, arrange-
ment and construction of parts hereinafter
fully described, pointed out in the appended
claims and illustrated in the accompanying
drawings, it being understood that many
changes may be made in the size and pro-
portion of the several parts and details of
construction, within the scope of the ap-
pended claims without departing from the
spirit or sacrificing any of the advantages
of the invention.

Broadly speaking, the invention consists of a parachute substantially in the form of a folding umbrella, which is provided with a hollow staff into which air is adapted to be forced as the parachute descends. The air flows from the hollow staff into a life saver-like contrivance, that is attached to the body of the aviator.

One of the many possible embodiments of the invention is illustrated in the accompanying drawings, in which:—

Figure 1 is a vertical section taken 45 through a parachute constructed in accordance with the present invention in its folded state, its covering being removed to more clearly show the construction; Fig. 2 is a similar section taken through a portion of 50 the parachute in its extended position; Fig. 3 is a section taken through the parachute staff and its runner; Fig. 4 is a central section taken through the top of the staff; Fig. 5 is a section taken on line 5—5 of Fig. 4; 55 Fig. 6 is a section taken on line 6—6 of Fig. 2; Fig. 7 is a section taken through a detail

of construction of a joint between the folding sections of the ribs of the parachute; Fig. 8 is a section taken through the life saver coöperating with the parachute; Fig. 9 is a section taken through the lower portion of the staff of the parachute and the connecting means between the same and the life saver; Fig. 10 is a section taken at right angles to that shown in Fig. 9; Fig. 11 is a section taken on line 11—11 of Fig. 10; Fig. 12 is a section taken on line 12—12 of Fig. 10; Fig. 13 is a section taken on line 13—13 of Fig. 10; Fig. 14 is a section taken on line 14—14 of Fig. 10; and Fig. 15 is a detail of the device shown in Fig. 10. 60 65 70

In the drawings, the numeral 20 indicates a tubular staff, to the upper end of which is attached in any suitable manner a casing 21, having two passages 22, that lead 75 to the interior of the staff 20, said passages being provided with air inlet ports 23 in their sides, as clearly shown in Fig. 5 of the drawings. To the casing is attached a crown 24, to which are pivoted ribs 25 in a manner well known in the umbrella art. The number of these ribs may be varied according to the requirements. The ribs are each made of two sections 26 and 27, which are pivoted to a connecting piece 28 at 29 and 30, respectively. To this connecting piece are secured a plurality of leaf springs 31, arranged in a semi-circular form, the two outermost ones of the springs abutting 85 against the rib sections, as clearly shown in 90 Fig. 2 of the drawings. To each rib section is pivoted a link 32, connected by a member 33, that is provided with a perforation 34, in which is seated a spindle 36, the latter being attached to the connecting piece 28. Around the spindle is coiled a spring 37, that bears against the member 33 and the connecting piece 28. The spring 37 aids the 95 action of the springs 31 in extending the rib sections when the parachute is being opened. 100

A spring 38 is attached to each section 26 of the ribs, said springs bearing against the respective rib sections 27, when the parachute is folded (Fig. 1), and aid also in the opening action of the springs above referred to. With each spring 38 co-operates a catch 39, that is carried by the section 26 of each rib, said catch being made use of when the parachute is being folded to prevent the corresponding section 27 of the rib from being extended while the others are being folded. 110

The ribs may be of any suitable con-

struction. In the case illustrated in the drawings, for instance, they are made of two sheet metal sections 40 and 41, that are riveted together and reinforced by wires 42. 5 Perforations 43 are provided at suitable intervals in the ribs for receiving the thread or other means that attaches the covering of the parachute to the said ribs. To each rib section 26 is pivoted at 44 the outer end 10 of a brace 45, its inner end being fulcrumed at 46 to a runner 47, which is slidably disposed in the usual manner upon the staff. This runner carries a plurality of telescoping tubes 48, which are disposed coaxially 15 with the staff, and connected by springs 49, each of the latter being inclosed by two adjacent telescoping tube sections. The uppermost of the springs, denoted by the numeral 49', bears against the uppermost of 20 the telescoping tube sections and against a disk-shaped member 50, that is fixedly attached to the staff 20. Below the casing 21 there is attached to the staff a stop 51 for the telescoping tube sections 48. To each 25 brace 45 is pivoted at 52 an auxiliary brace 53, the latter being fulcrumed at 54 to a second runner, denoted by the numeral 55. This runner is slidably disposed upon a tubular extension 56 of the runner 47. Between the two runners is located a spring 57. The tubular extension 56 of the runner 47 is provided with two lugs 58, that are adapted to be engaged by spring pressed catches 59, the latter being pivoted at 60 to 30 a disk 61, that is attached to the staff 20 near its lower end. To the disk 61 are fastened stay-cords 62 and 62', each cord 62 being attached to a link 63, that is pivoted to a connecting piece 28 between the rib sections 26 and 27, and each stay-cord 62' being fastened to the tip of a section 27 of a rib. 35 To the lower end of the staff 20 is attached a joint 64. This joint comprises a hollow substantially O-shaped member, that 40 communicates with the tubular staff, and is provided with outlets 65 leading to a conical seat 66, that is open at one of its sides, as shown at 67, to permit of a sideward insertion thereinto of the conical end 68 of a tube 45. This tube is carried by a bracket 70, which is fastened to a shield 71, the latter being adapted to be attached to the arm of 50 the aviator. Upon the bracket are arranged lugs 72, that fit into recesses 73 in a block 55 74, the latter being secured to the joint 64. The upper end of the conical portion 68 of the tube 69 is closed, for instance by a disk 75, that is carried by a spindle 75', the latter being slidably disposed in the bracket 70 60 and held in its closing position by a spring 76. The tube 69 leads to a life saver 77, which is held upon the body of the aviator, and is made in the form of an inflatable body, as clearly shown in Fig. 8 of the drawings. In the tube 69 is arranged a valve cas-

ing 78, in which is disposed a check valve 79, that permits of a passage of air from the staff 20 to the life saver, but prevents a return thereof.

The operation of this device is as follows: The life saver 77 is normally attached to the body of the aviator, the bracket 70 being held upon one of his arms with the parts attached thereto. The parachute is disposed upon the aerial vessel in its folded or collapsed position (Fig. 1). When the parachute is in its closed position, the catches 39 are disengaged from the springs 38, the latter together with the springs 37 and 49 being held under tension by the 75 catches 59 in engagement with the lugs 58 upon the tubular extension 56 of the runner 55. In case of danger or accident, the aviator inserts laterally the conical end 68 of the tube 69 into the conical seat 66 of the joint 64. By this operation the lugs 72 are brought into the recesses 73 in the block 74. By pulling then the bracket 70 downward until the parts are brought into the positions shown in Fig. 10 of the drawings, 80 the lugs 72 prevent the bracket from becoming disengaged from the joint 64. When the parts are in these positions, the outlets 65 in the joint 64 register with inlets 80 in the conical portion 68 of the tube 69. The operator then disengages the catches 59 from the lugs 58, whereby the parachute is automatically opened, the parts being brought into the positions shown in Fig. 2 of the drawings, permitting thus of a safe 85 descent of the aviator. In descending, air is forced through the ports 23 in the passages 22 into the tubular staff 20, the air passing through said staff and through the joint 64 to the tube 69, and through the latter into the life saver 77, which will thus be inflated. The inflated life saver aids in the 90 safe descent of the aviator. 105

What I claim is:

1. In a device of the character described, 110 the combination with a foldable parachute having a tubular staff provided with air inlet ports immediately below the covering of the parachute, of an inflatable life saver adapted to be attached to the body of the 115 aviator, and a tube connecting said hollow staff with said life saver.

2. In a device of the character described, 120 the combination with a foldable parachute having a tubular staff provided with air inlet ports immediately below the covering of the parachute, of an inflatable life saver adapted to be attached to the body of the aviator, a tube leading from said life saver, and coacting separable means for connecting said tube with said hollow staff. 125

3. In a device of the character described, 130 the combination with a foldable parachute having a tubular staff provided with air inlet ports immediately below the covering of

- the parachute, of an inflatable life saver adapted to be attached to the body of the aviator, a tube leading from said life saver, coacting separable means for connecting said tube with said hollow staff, and means for attaching that portion of said connecting means which is associated with said tube to the arm of the aviator.
4. In a device of the character described, 10 the combination with a foldable parachute having a tubular staff provided with air inlet ports immediately below the covering of

the parachute, of an inflatable life saver adapted to be attached to the body of the aviator, a tube connecting said hollow staff 15 with said life saver, and a check valve in said tube.

Signed at Witherbee, in the county of Essex and State of New York, this 7th day of Dec., A. D. 1914.
